(57) **CLAIM**

We claim the ornamental design for a slider pull, as shown and described.

DESCRIPTION

FIG. 1 is a bottom, right, front perspective view of a first embodiment of the slider pull;

FIG. 2 is top side elevation view thereof;

FIG. 3 is a front elevation view thereof;

FIG. 4 is a bottom side elevation view thereof;

FIG. 5 is a left side elevation view thereof, the right side elevation view being a mirror image thereof;

FIG. 6 is a back elevation view thereof;

FIG. 7 is a bottom, right, front perspective view of a second embodiment of the slider pull;

FIG. 8 is top side elevation view of the second embodiment thereof;

FIG. 9 is a front elevation view of the second embodiment thereof;

FIG. 10 is a bottom side elevation view of the second embodiment thereof;

FIG. 11 is a left side elevation view of the second embodiment thereof; the right side elevation view being a mirror image thereof;

FIG. 12 is a back elevation view of the second embodiment thereof;

FIG. 13 is a bottom, right, front perspective view of a third embodiment of the slider pull;

FIG. 14 is top side elevation view of the third embodiment thereof;

FIG. 15 is a front elevation view of the third embodiment thereof;

FIG. 16 is a bottom side elevation view of the third embodiment thereof;

FIG. 17 is a left side elevation view of the third embodiment thereof; the right side elevation view being a mirror image thereof; and,

FIG. 18 is a back elevation view of the third embodiment thereof.

The broken lines are for illustrative purpose only and form no part of the claimed design.
